UNITED STATES PATENT OFFICE

158,295

FLATIRON

Ralph E. Kruck, Clinton, Conn., assignor to Westinghouse Electric Corporation, a corporation of Pennsylvania

Application April 19, 1949, Serial No. 2,138

Term of patent 14 years

(Cl. D49—6)

To all whom it may concern:

Be it known that I, Ralph E. Kruck, a citizen of the United States, residing at Clinton, in the county of Middlesex and State of Connecticut, have invented a new, original, and ornamental Design for a Flatiron, of which the following is a specification, reference being had to the accompanying drawings, forming a part thereof.

Figure 1 is a front perspective view of a flatiron embodying my new design;

Figure 2 is a plan view thereof; and

Figure 3 is a rear perspective view thereof.

I claim:

The ornamental design for a flatiron, substantially as shown.

RALPH E. KRUCK.
